The ornamental design for a miniature electric par lamp, as shown and described.

DESCRIPTION

FIG. 1 is a perspective view of a miniature electric par lamp illustrating the new design;

FIG. 2 is a side elevational view thereof, all sides being identical;

FIG. 3 is top view thereof; and,

FIG. 4 is bottom view thereof.

In all of the foregoing drawings, stippling is intended to illustrate shape and contour; such stippling is further intended to illustrate surface characteristics.
